Fig. 3.

Fig. 4.

FIG. 1 is a front elevational view of a set of chess pieces showing our new design;

FIG. 2 is a bottom plan view thereof;

FIG. 3 is a side elevational view thereof; and

FIG. 4 is a rear elevational view thereof.

The essential feature of our design is the combination of the vertical fluted sides with the slanted tops.

A typical pawn is shown in dotted lines.

We claim:

The ornamental design for a set of chess pieces, substantially as shown and described.
